United States Patent Office

Des. 186,276
Patented Oct. 6, 1959

186,276

GOLF PRACTICE DEVICE

James R. Neiler, Olean, N.Y.

Application April 3, 1959, Serial No. 55,342

Claims priority, application Canada October 7, 1958

Term of patent 14 years

(Cl. D34—5)

Fig. 1 is a perspective view of a golf practice device, showing my new design; and

Fig. 2 is a sectional view thereof taken about on line 2—2 of Fig. 1.

I claim:

The ornamental design for a golf practice device, substantially as shown.
